METHOD OF PACKAGING LIVE LOBSTERS

Joseph R. Macdonald, Winchester, Mass.

Application August 31, 1939, Serial No. 292,847

4 Claims. (Cl. 119—2)

The present invention relates to a method of packaging live lobsters and keeping them alive for a considerable period of time, during storage or shipment.

It is well known that lobsters, after being caught, are usually kept for some time upon ice. But they do not survive more than a day or two, ordinarily, under such treatment. And when a lobster dies from natural causes, it is not safe to be used for food purposes.

It is therefore an object of the present invention to provide a method of keeping lobsters alive for a considerable period of time, either for local storage and delivery or for shipment to considerable distances, or both. It is also an object to provide means whereby a single lobster or a small number of lobsters may be kept and transported, conveniently and safely. Other objects will appear from the following disclosure.

By the present invention it is found that if the freshly caught, live lobster is put into a container, in a sufficient amount of water to cover the lobster, preferably while oxygen is being passed through the water, and a cover is then put on which is capable of hermetically sealing the can, the lobster may thereby be kept alive many days. The introduction of oxygen may be discontinued after the concentration of oxygen added, together with the oxygen of the air left in the container is substantially increased but preferably after the air has been completely displaced. Or it may be continued gradually and uniformly, until a pressure is developed in the container, which may ultimately be substantially equivalent to that under which the lobster normally lives. In either case, when a suitable addition of oxygen has been made it is then shut off and the container closed so as to maintain such condition or pressure (e. g., 3 to 40 pounds per square inch above atmospheric pressure), and the lobster will live in the closed container for many days or even weeks. Moreover, the lobster will not only be alive and healthy, but livelier and more healthy than when put in.

Several typical examples of the practical application of the invention, with different kinds of containers, will be described, with reference to the accompanying drawing in which:

Fig. 1 is a side view, with a portion broken away, of a cardboard carton with a metal bottom and friction-seal metal cover;

Fig. 2 is a perspective view of an all-metal can, having a friction-seal metal cover;

Fig. 3 is an enlarged radial cross-section of a portion of the top edge and cover of the can in Fig. 2;

Fig. 4 is an enlarged radial cross-section of a portion of the bottom and side wall of the can shown in Fig. 2;

Fig. 5 is a side elevation, with parts broken

away, of a lobster as packed in a transparent Cellophane container;

Fig. 6 is a diametrical cross-section of the valve on the container in Fig. 5 along the line 6—6; and

Fig. 7 is a cross-section of the rolled edge seam of the container in Fig. 5 along the line 7—7.

For purposes of making small shipments of lobsters as above described, the method of the invention may be adapted to sizeable containers for a considerable number of lobsters or to individual containers, with a single lobster in each.

Thus, as shown in Fig. 1, a carton having a cardboard body portion 1, a metal bottom 2, an open metal top rim 3, and a tight-fitting friction cover 4 may be used. The lobster may be placed in the carton, with sufficient sea water to cover it, as indicated at 5.

A one-way gas valve 6 is previously fastened 20 through the bottom 2, as shown. The cover may now be fitted in place on the body portion. Before and while the lobster is being placed in the can, as well as thereafter, oxygen may be passed through the soft rubber valve 6 by connecting to 25 any convenient source of compressed oxygen gas as by inserting a needle 15 therethrough as shown in Fig. 4. The cover is then closed and sealed, and the oxygen continued long enough to develop the desired pressure. The source of oxygen is 30 then withdrawn by retracting the needle 15, whereupon the valve 6 automatically closes and the package is hermetically sealed, ready for shipment. The carton may be made of water 35 resistant material, such as waterproof cardboard or provided with an especially impenetrable liner 7 on the inside.

The valve 6 may be of any appropriate construction but conveniently is fashioned of soft rubber with a large mushroom head 11, having 40 a thin, soft, downwardly curved periphery 12 and a stem 13 which is passed (from the inside of the can) through a somewhat smaller hole 14 in the tin bottom of the carton 2, provided to receive it. The oxygen is introduced through a sharp, hollow 45 needle 15 which is inserted through the stem and mushroom head and leads from a suitable supply of compressed oxygen (not shown) to deliver oxygen into the can uniformly and at such pressure as to develop the pressure ultimately required, which may vary from about 3 pounds to 50 40 pounds per square inch above that of the atmosphere. When the desired pressure in the can has been provided, the stem 13 is pulled, drawing the narrow shoulder 16 thereon through the hole 55 14 and the needle is also withdrawn. The soft rubber closes up the aperture which has been formed and left by thus inserting the needle and the shoulder 16 holds the mushroom head and especially its periphery 12 under tension against the inside of the can, thus effectively sealing it

against escape of the compressed oxygen or water in the container.

Another form of container suitable for larger numbers of lobsters, as shown in Fig. 2, may comprise a tin can 21 having a usual body portion 22 and a friction cover 23 such as is customarily used on paint cans. If more than one lobster is to be packed, they may be inserted back to back, or one on top of the other, as shown in Fig. 2, or a false bottom 24 of wire screening may be provided, standing somewhat above the bottom to provide a sump portion 25, in which solids and heavy matter may collect by sedimentation. Additional wire trays or shelves 26 may be placed in the can to keep the lobsters apart, to advantage. In packing, the lobsters are covered with sea water, which may already have been treated with oxygen, and oxygen then introduced through the one way gas valve 28 (similar to valve 6 above described) passing through the bottom 27 and retained by a shoulder 30. The cover 23 is then put in place and may be soldered as at 29. The oxygen is continued so as to expel air through the hole 20, in the cover, which is then closed with a drop of solder. The introduction of oxygen is continued, to deliver the required amount or to develop the required pressure in the can, or both. The source of oxygen is then disconnected, by withdrawing the needle 15 as above described, and the one-way valve automatically closes against loss of oxygen or water, in the same manner, and the loaded can is ready for shipment.

A further form of container 31, which is shown in Figs. 5-7, may be made of waxed Cellophane or other water-resistant transparent sheet material 32, rolled to form a hollow cylinder, and sealed along its joined edges 33 and then sealed and clamped at one end (by folding the material on itself at least twice), as at 34 and attaching a metal clamp 35, under pressure, with gripping projections 36, to hold it in place. The container thus formed may then be charged with the lobster and enough water to cover it, through the open end 37. The sea water is preferably treated with oxygen either previously or while being arranged for and while packing the lobster or lobsters therein. The one-way valve 41, which is initially mounted in the Cellophane wall as shown in Fig. 6, serves for the introduction of oxygen under pressure.

The oxygen is introduced from a suitable source, through the valve 41, which may in this instance be constructed and applied as above described or with the assistance of a concave disc of metal 42 with a hole 43 in the middle, through which the stem 44 is drawn and which grips the stem 44 against retraction and holds the mushroom rubber head 45 of the valve with its thin periphery 46, firmly and gas tight against the inside surface of the Cellophane, even though the latter may be very thin.

The open end 37 is then closed, as by rolling the edges together and clamped by a metal clamp similar to clamp 36, to hermetically close and seal this end, as with the end 34. When the air has preferably been first displaced by oxygen and a sufficient amount and/or pressure of oxygen has been provided (e. g., to keep the lobster or lobsters alive at least three days), after closing the end 37, the oxygen supply is disconnected by withdrawing the needle 15, through the thread-like hole 47, and thereupon the soft rubber of the valve around the thread-like hole 47 automatically closes behind it and hermetically seals and

retains the contents of the container under pressure. The latter may then be conveniently carried, stored or shipped for considerable periods of time and for considerable distances. The particular advantage of the Cellophane container is, of course, that the lobster may be seen and inspected from time to time, without opening. The lobster might also be cooked without removing from the container and while still in the sea water, if desired.

As thus packaged and submerged in sea water, saturated with oxygen at least at a high concentration and preferably containing additional oxygen under appreciable pressure,—e. g., substantially equivalent to that of the sea water in which the lobster has been accustomed to live,—a lobster will not only remain alive for 7 to 10 days, but is found to be actually healthier and livelier at the end of this time than when put into the container. Moreover, when used as a food, the meat of such a lobster is in many respects improved as to quality and flavor over that of a lobster as freshly caught. The physiological reasons why this is so need not be entered into, but it is an observed fact.

It may also be observed that, while the invention has been described with particular reference to lobsters and the problem of keeping them alive,—which is an especially difficult problem and requires the provision of exacting care and conditions of treatment,—it may also be readily applied to the preservation of shell fish, such as clams, oysters, crabs and the like, to advantage.

I claim:

35 1. Method of keeping lobsters alive, comprising the steps of putting a live lobster into a container with sufficient sea water completely to submerge its body, while passing oxygen into the container through the water, closing the container, continuing the introduction of oxygen to produce a concentration of oxygen greater than that of the atmosphere, and finally hermetically sealing the container.

45 2. Method of keeping lobsters alive, comprising the steps of putting a live lobster into a container with sufficient sea water completely to submerge its body, while passing oxygen into the container through the water, closing the container, continuing the introduction of oxygen to produce a concentration of oxygen greater than that of the atmosphere, and a pressure of 3 to 40 pounds per square inch above atmospheric pressure, and finally hermetically sealing the container.

50 3. Method of keeping lobsters alive, comprising the steps of putting a live lobster into a container with sufficient sea water completely to submerge its body, while passing oxygen into the container to displace the air therein, closing the container, continuing the introduction of oxygen into and through the water in the container, to produce a pressure in the container substantially equivalent to that of the sea water in which lobsters usually live, and finally hermetically sealing the container.

55 4. Method of keeping lobsters alive, comprising the steps of putting a live lobster into a container with sufficient sea water, the oxygen content of which has been increased by preliminary contact with concentrated oxygen, to cover the under portion of the lobster, closing the container, introducing oxygen to produce a concentration of oxygen greater than that of the atmosphere, and hermetically sealing the container.

JOSEPH R. MACDONALD.
